UNITED STATES PATENT OFFICE

2,531,661

CARBURETOR

Otto Alfred Arvastsson, Malmo, Sweden

Application November 25, 1946, Serial No. 712,086
In Sweden August 17, 1940Section 1, Public Law 690, August 8, 1946
Patent expires August 17, 1960

3 Claims. (Cl. 261—14)

1

My invention relates to improvements in carburetors for internal combustion engines, and it consists in the combination, construction and arrangement hereinafter described and claimed.

An object of my invention is to provide a carburetor permitting efficient use of relatively heavy fuels or fuels having a relatively high content of water.

Another object of the invention is to provide a carburetor of a simple and reliable construction suitable for relatively heavy fuels or fuels having a relatively high content of water.

My improved carburetor is of the type comprising a mixing chamber having a main air inlet and an outlet to be connected to the intake manifold of the engine, a fuel nozzle opening into the mixing chamber, a float chamber with which the fuel nozzle communicates, and a valve which under the control of the float in the float chamber controls the supply of fuel to the float chamber. In carburetors of this type it is already known, for instance from the Swedish Patents Nos. 69,202 and 71,123, to provide a heating chamber fitted with heating elements around the float chamber and to provide this heating chamber with an air inlet from atmosphere and with an air outlet opening into the mixing chamber of the carburetor, so that the heating elements in said heating chamber may be utilized for heating both the fuel in the float chamber and part of the air entering the mixing chamber. One object of my invention is to improve carburetors provided with heating means of this special nature for both the fuel and part of the air. The improvements consist largely in such an arrangement of the air outlet from the heating chamber and the fuel nozzle opening into the mixing chamber that the said outlet for the heated air from the heating chamber surrounds the fuel nozzle and serves the purpose of causing the heated air to atomize or vaporize the fuel from the fuel nozzle before the forming mixture of the atomized or vaporized fuel and the heated air are allowed to mix with the rest of the air in the mixing chamber. I have found this arrangement to result both in a very simple and reliable construction of the carburetor and in the possibility of using relatively heavy fuels and fuels with a relatively high content of water, for instance motor alcohol with a water content of up to about 20%.

My invention is illustrated in the accompanying drawing, in which

Fig. 1 is a vertical section of a carburetor constructed according to my invention, and

2

Fig. 2 is a horizontal section substantially on the line II—II in Fig. 1.

The drawing is somewhat diagrammatic, parts not necessary for the understanding of the invention being omitted for the sake of clearness.

As shown on the drawing the carburetor comprises a float chamber 1 and a mixing chamber 2. The mixing chamber 2 is provided with a main air inlet 3 and an outlet 4 which latter is adapted to be connected to the intake manifold of the engine. The air inlet 3 is provided with a choke valve 5, and the outlet 4 is provided with the usual mixture throttle valve 6. The fuel is supplied through a pipe 7 and enters the float chamber 1 through a valve 8 under the control of the float 9. Around the float chamber 1 there is a heating chamber 10 provided with an air inlet 11 and fitted with electric heating elements 12 and having an air outlet opening into the mixing chamber 2 as will be described more in detail hereinafter. The heating chamber 10 can be heated not only by the electric heating elements 12 therein but also by exhaust gases from the internal combustion engine, for which purposes there is provided outside of the heating chamber 10 a chamber or channel 13 which preferably may extend also around the mixing chamber 2 and has an inlet 14 and an outlet 15 for the exhaust gases. From the float chamber 1 the fuel passes through a passage 16 to a nozzle 17 projecting centrally in the mixing chamber 2 from the bottom thereof. The communication between the nozzle 17 and the fuel passage 16 may be adjustable by means of an adjusting valve 18. The heating chamber 10 has an extension 19 extending beyond and embracing the base portion of the nozzle 17 and having in its top wall an opening fitted with a tubular member 20 concentrically surrounding and preferably projecting somewhat above the nozzle 17 in the mixing chamber 2 and forming the outlet into the latter for the air heated in the heating chamber 10.

Obviously part of the air will be sucked into the mixing chamber 2 through the heating chamber 10, and the rest of the air will be drawn in through the main air inlet 3. I prefer to heat the heating chamber 10 by means of the electric heating elements 12 only before and during starting of the engine when cold, and to facilitate the starting the main air inlet 3 may be choked by means of the choke valve 5. During normal working of the engine the heating of the heating chamber 10 is effected preferably only by passing part of the hot exhaust gases from the en-

gine through the chamber or channel 13, the main part of the air being sucked in through the main air inlet 3. The smaller part of the air sucked in through the heating chamber 10 is heated therein, and because of the disposition of the heating chamber 10 around the float chamber 1 also the fuel therein is heated. On account of the arrangement of the tubular outlet 20 for the heated air into the mixing chamber 2 the heated air from the heating chamber 10 will pass the nozzle 17 and atomize or vaporize the fuel before the forming mixture of the heated and atomized or vaporized fuel and the heated air are allowed to mix with the rest of the air sucked in through the main air inlet 3. By thus heating the fuel in the float chamber 1 and part of the air in the surrounding heating chamber 10 and utilizing only this heated relatively small part of the air for effecting atomization or vaporization of the fuel from the fuel nozzle 17 before allowing the forming mixture of the heated air and the atomized or vaporized fuel to mix with the main part of the air in the mixing chamber 2 I obtain the advantage of making possible an efficient use of relatively heavy fuels and fuels with a relatively great water content in conventional automobile and like engines which otherwise require relatively light fuels. As will be seen from the drawing the carburetor according to the invention is of a very simple construction and, therefore, relatively cheap in manufacture and reliable in action. If desired an additional fuel passage 21 may be branched off from the fuel passage 16 and open into the upper part of the mixing chamber 2 and be provided with suitable control means as diagrammatically indicated at 22.

What I claim and desire to secure by Letters Patent is:

1. A carburetor for internal combustion engines comprising a float chamber, a mixing chamber having a main air inlet and an outlet to be connected to the intake manifold of the engine, said main air inlet being open to the atmosphere and constituting a direct extension of said mixing chamber, a tubular fuel vaporizing chamber vertically arranged in said mixing chamber and opening into said mixing chamber, a fuel nozzle in said tubular fuel vaporizing chamber vertically and concentrically arranged therein and communicating with said float chamber, the upper end of said fuel nozzle being substantially below the upper edge of said tubular vaporizing chamber, a heating chamber surrounding said float chamber and having an air inlet, an extension on said heating chamber constituting a heated air outlet, said heated air outlet opening into the lower end of said tubular fuel vaporizing chamber around said fuel nozzle, and heating means in said heating chamber whereby air enters said heating chamber and upon being heated by said heating means heats said float chamber and fuel therein and subsequently passes into said tubular fuel vaporizing chamber, ejecting heated fuel from said nozzle into said tubular chamber, vaporizing and further heating the heated fuel in said chamber, unheated air from said main air

inlet passing the open end of said tubular chamber into said mixing chamber and ejecting the heated and vaporized mixture from said tubular fuel vaporizing chamber into said mixing chamber for further mixing with the unheated air from said main air inlet open to the atmosphere before entering the engine through said intake manifold.

2. In a carburetor for internal combustion engines as claimed in claim 1, an auxiliary heating chamber surrounding said heating chamber and said mixing chamber, said auxiliary heating chamber having an inlet and an outlet, said inlet being connected to the exhaust manifold of said engine.

3. A carburetor for internal combustion engines comprising a float chamber, a mixing chamber having a main air inlet and outlet to be connected to the intake manifold of the engine, said

20 main air inlet being open to the atmosphere and constituting a direct extension of said mixing chamber, a tubular fuel vaporizing chamber vertically arranged in said mixing chamber and opening into said mixing chamber, a fuel nozzle

25 having lateral openings in proximity to the top thereof in said tubular fuel vaporizing chamber vertically and concentrically arranged therein and communicating with said float chamber, the lateral openings in said fuel nozzle being below

30 the upper edge of said tubular vaporizing chamber, a heating chamber surrounding said float chamber and having an air inlet, an extension on said heating chamber constituting a heated air outlet, said heated air outlet opening into the

35 lower end of said tubular fuel vaporizing chamber around said fuel nozzle, heating means for said heating chamber whereby air enters said heating chamber and upon being heated by said heating means heats said float chamber and fuel therein

40 and subsequently passes into said tubular fuel vaporizing chamber, ejecting heated fuel from said nozzle into said tubular chamber, vaporizing and further heating the heated fuel in said chamber, unheated air from said main air inlet pass-

45 ing the open end of said tubular chamber into said mixing chamber and ejecting previously heated and vaporized mixture from said tubular vaporizing chamber into said mixing chamber for further mixing with the unheated air from said

50 main air inlet open to the atmosphere before entering the engine through said intake manifold.
